UNITED STATES PATENT OFFICE

121,814

DESIGN FOR A COMBINATION LAVATORY AND CABINET

Leonard Keller, Ferndale, Mich., assignor to The Murray Corporation of America, Detroit, Mich.,
a corporation of Delaware

Application December 1, 1939, Serial No. 88,610

Term of patent 7 years

To all whom it may concern:

Be it known that I, Leonard Keller, a citizen of the United States of America, residing in Ferndale, in the county of Oakland, State of Michigan, have invented a new, original, and ornamental Design for Combination Lavatory and Cabinet, of which the following is a specification, reference being had to the accompanying drawing, forming a part thereof, wherein:

The figure shows a perspective view of a combination lavatory and cabinet showing my new design.

I claim:

The ornamental design for a combination lavatory and cabinet, substantially as shown.

LEONARD KELLER.
